DESIGN FOR A SLIDE FASTENER

Noel J. Poux, Meadville, Pa., assignor to Talon,
Inc., Meadville, Pa., a corporation of Penn-
sylvania

Application August 31, 1939, Serial No. 86,984

Term of patent 14 years

To all whom it may concern:

Be it known that I, Noel J. Poux, a citizen of the United States, residing at Meadville, in the county of Crawford and State of Pennsylvania, have invented a new, original, and ornamental Design for Slide Fasteners, of which the following is a specification, reference being had to the accompanying drawing, forming a part thereof.

In the drawing:

Fig. 1 is a perspective front view of a slide fastener according to this design;

Fig. 2 is a plan view of the front of the slide fastener shown in Fig. 1; and

Fig. 3 is a plan view of the back of the slide fastener shown in Figs. 1 and 2.

I claim:

The ornamental design for a slide fastener, substantially as shown.

NOEL J. POUX.
